UNITED STATES PATENT OFFICE.

SIMEON S. JACKSON, OF HYDE PARK, BOSTON, MASSACHUSETTS, ASSIGNOR TO THE STAFFORD COMPANY, OF BOSTON, MASSACHUSETTS, A CORPORATION OF MASSACHUSETTS.

WEFT-END HOLDER FOR WEFT-REPLENISHING LOOMS.

Application filed September 8, 1923. Serial No. 661,548.

To all whom it may concern:

Be it known that I, SIMEON S. JACKSON, a subject of Great Britain, residing at Hyde Park, Boston, in the county of Suffolk, 5 State of Massachusetts, have invented a certain new and useful Improvement in Weft-End Holders for Weft-Replenishing Looms, of which the following is a specification, reference being had therein to the 10 accompanying drawings.

The invention is designed for employment in weft-replenishing looms of the type in which reserve weft or filling carriers are supported in a rotatable magazine, from 15 which they are transferred one by one to the working shuttle by the action of the automatic weft-replenishing devices. It relates in particular to the weft-end holders which are provided in connection with such 20 magazines to hold the starting ends of the weft or filling yarns of the said carriers so as to cause the automatic threading of a working shuttle when a new supply of weft or filling has been placed within the 25 shuttle.

The usual form of weft-end holder, detachably affixed to the outer end of a rotatable magazine, in axial alignment with the magazine, comprises a shank having at 30 its outer end a knob with partly spherical exterior. The said shank is tapered slightly from the knob inward toward the end thereof by which the device is engaged with the hub of the bell-shaped outermost circular 35 plate of the magazine. At the time of placing a fresh filling carrier in the magazine, the starting end of the weft or filling yarn wound on the said carrier is drawn by the weaver outward from the tip end of the 40 carrier, bent inwardly over the edge of said bell-shaped plate, and then wrapped around the weft-end holder alongside its knob. The surfaces of the knob and shank customarily are smooth, and the shank is 45 tapered, to facilitate the operation of slipping an accumulated mass of weft or filling yarns off the holder after the latter has been temporarily detached from the magazine for the purpose of being stripped.

50 The said usual form of weft-end holder, just described, has the disadvantage or drawback that an empty or clean holder permits an undesirable slackening of the first weft-ends that are engaged therewith. That

is to say, the first few coils or turns of a 55 weft-end or ends that are wound on a clean holder at the junction of the shank and knob have a tendency to work or slip inward along the cone, away from the knob, to shank-portions of smaller diameter. This 60 results in loosening of the said coils or turns, and in slackening of the weft-end between the filling carrier and the weft-end holder, and sometimes the weft-end hangs down 65 and is caught upon the picker-stick. The tendency to this slipping, loosening, etc., is noticeable particularly in the case of yarns of a smooth slippery character, such as rhea or ramie.

The general object of the invention is to 70 obviate the disadvantage or drawback aforesaid by providing a weft-end holder which shall be so constructed as to prevent the inward slipping, loosening, and slackening, 75 etc., to which reference has been made.

My invention comprises a weft-end holder 80 consisting in a knob, a shank by means of which to engage the holder with a magazine, and a sleeve that is removably mounted upon said shank and formed with a conical 85 exterior tapering toward the knob; preferably with the small end of said sleeve rounded off or chamfered to leave a small V-shaped space between the sleeve and the knob into which the first few turns of filling wound upon the holder may enter.

An embodiment of my invention is shown in the accompanying drawings, in which,—

Fig. 1 is a sectional view of the bell-shaped outermost disk of a rotatable magazine and its central mounting, showing the 90 said embodiment of the invention applied thereto.

Fig. 2 shows the weft-end holder of Fig. 1, separately, partly in longitudinal section.

Fig. 3 is an end view of the said holder, looking at the same from the left hand side in Figs. 1 and 2.

In the drawings,—

At 1 is a disk of bell shape such as is commonly employed at the outer end of one of the well-known forms of rotatable weft-holding magazines employed in connection with weft-replenishing looms. It is provided with a hub 2 adapted to be secured by clamping screw 3 upon a loose sleeve 4 turning upon a stud 5 which in practice is supported by 100 105

suitable means from the breast-beam of the loom. The hub 2 is provided with an axial bore to receive the inner end of the shank 8 of the weft-end holder, such shank being securely held therein by a clamping screw 6.

The illustrated weft-end holder comprises a knob 7, a shank 8 formed integrally with the knob, the said shank being cylindrical throughout the greater portion of its length, and a sleeve 9 mounted upon said shank and having a conical exterior. The small end of said sleeve is outermost and is rounded off or chamfered as shown at 10 so that when such end is pushed up against the inner surface of the knob 7 a slight V-shaped annular groove 11 will be left between the small end of the sleeve and the knob 7. The knob 7 is cut away, at the point where the shank joins it, to form an annular surface at right angles to the axis of the shank, and the small end of the sleeve contacts with this annular surface. To secure the sleeve 9 against rotation upon the shank 8, a pin or key 12 is fixed in the knob 7 parallel to the surface of the shank, and is received within a hole provided in the small end of the sleeve 9. The inner end of the shank is flattened as shown at 13 for engagement by the clamping screw 6 to hold it in the hub 2 of the disk 1 and cause it to turn in unison therewith.

In use, the first few turns of weft-ends are wound about the weft-end holder at the junction of the knob 7 and the sleeve 9, wedging within the V-shaped groove 11. The engagement of the first few turns in the said groove prevents their unwinding, and they in turn prevent the unwinding of the subsequently applied turns; while the

inwardly flaring shape of the cone-shaped sleeve obviates the tendency of the turns or coils which are wound thereon to slip inwardly along the end-holder and become slack by reason of such slipping.

When it is desired to remove the accumulation of weft-ends from the holder, the screw 6 is loosened and the whole holder detached from the magazine, and the sleeve 9 slipped off from the shank 8. The accumulated mass of yarns may then be easily slipped by hand from the sleeve, and from the knob and its stem, without resort to the practice of cutting and hacking off with a knife.

I claim as my invention,—

1. A weft-end holder for weft-replenishing looms comprising a knob, having a shank which is fixedly connected therewith, and a sleeve mounted upon said shank, removable therefrom by movement away from the knob, having a conical exterior, with the small end of such sleeve adjacent the knob.

2. A weft-end holder for weft-replenishing looms comprising a knob, a shank, and a sleeve removably mounted upon said shank having a conical exterior tapering toward the knob, and also having its small end chamfered to form a yarn-receiving groove alongside the knob.

3. A weft-end holder for weft-replenishing looms comprising a knob, a shank, a sleeve removably mounted upon said shank having a conical exterior tapering toward the knob, and also having its small end chamfered to form a yarn-receiving groove alongside the knob, and means to lock the sleeve to prevent relative rotation.

SIMEON S. JACKSON.
